BAG FEED MECHANISM

Raymond Althoff, Brooklyn, N. Y., assignor to
 Bagomatic, Incorporated, Brooklyn, N. Y., a
 corporation of New York

Application October 18, 1947, Serial No. 789,665

17 Claims. (Cl. 112—10)

1

This invention relates to automatic bag sewing machinery and more particularly to apparatus for forming the free edges of a piece of bag material such as, for example, burlap into an export seam adapted to be sewed by a sewing machine.

In the manufacture of sewed bags it is the usual practice to sew the bag inside out and then reverse the bag before it is filled with the material that is to be packed in the bag. The manufacturing operation is commonly carried out by folding a piece of bag material in half, sewing the free edges opposite the fold to form a side seam, sewing another pair of edges to form a bottom seam, and then turning the bag inside out. In order to provide additional strength, it is frequently desirable to make either the side seam or the bottom seam, or both, a so-called "export" seam.

The nature of an export seam and the general purpose of the present apparatus when applied to the making of such a seam may be conveniently illustrated and explained by reference to Figs. 1 and 2 of the accompanying drawings which show, respectively, the manner in which a piece of bag material is folded before being fed to a preferred embodiment of the present apparatus to form a side seam of the bag, and the manner in which the material is folded after it leaves this embodiment of the apparatus. Fig. 1 shows in cross-section a piece of burlap 10, folded in half to form the free edges 12 and 14. The burlap 10 is fed to the apparatus shown in Figs. 3—11 of the drawings, and described in detail hereafter, and the free edges 12 and 14 are automatically folded in such manner as to form the export seam 16 shown in Fig. 2 of the drawings. The seam 16, which is the side seam of the bag, can then be sewed in a conventional sewing machine.

In order to justify its initial high cost, an automatic bag sewing machine must produce bags at a relatively high rate as compared with the production rate that is manually attainable, or attainable with the use of semi-automatic machinery. Moreover, this high rate must be achieved without substantial reduction in the quality of the work, since if an appreciable number of bags is misfolded or mis-sewed, the loss due to rejected bags may offset the advantage of using the automatic machine. In general it may be said that the principal limitation upon bag sewing machinery has been, not the sewing machine itself, but rather the auxiliary apparatus for forming and handling the bag. Industrial sewing machines capable of sewing at very high rates are readily available, but the development of bag handling and bag forming machinery has not

2

kept pace with the development of the sewing machine itself.

It is accordingly an object of the present invention to provide improved apparatus for forming a folded seam in a piece of bag material that is to be sewed in a sewing machine. It is a further object of the invention to provide such a seam former that is capable of operating at a high rate of speed. It is another object of the invention to provide a seam former of this character that is simple in construction and accurate and reliable in operation. Other objects of the invention will be in part obvious and in part pointed out hereafter.

15 The many objects and advantages of the present invention may best be appreciated by reference to the accompanying drawings which illustrate apparatus incorporating a preferred embodiment of the invention and wherein:

20 Figs. 1 and 2, as previously described, are cross-sections of a piece of bag material before it enters the present apparatus and after it leaves the present apparatus respectively;

25 Fig. 3 is a general side elevation of the present seam former, showing its normal position with respect to that of the feed table and sewing machine presser foot;

30 Fig. 4 is a rear elevation of the seam former, showing the drive shafts and gearing for driving the various elements of the apparatus;

35 Fig. 5 is a top plan view of the interior of the seam former showing the separator disks, the fold-forming disks and the bag material edge guides;

40 Fig. 6 is a vertical section through the seam former, taken on the line 6—6 of Fig. 5 and showing in elevation the various parts depicted in Fig. 5;

45 Fig. 7 is a vertical section taken on the line 7—7 of Fig. 6 and showing the manner in which the fold-forming disks cooperate with one another;

50 Fig. 8 is a fragmentary section through one of the separator disk drive shafts, showing the manner in which the disengaging combs are mounted with respect to the separator disks;

Fig. 9 is a fragmentary section taken on the line 9—9 of Fig. 6 and showing two of the disengaging comb adjusting rods;

55 Fig. 10 is a detail view of the adjacent portions of the upper and lower separator disks, showing the manner in which they separate the edge portions of the bag material; and

Figs. 11, 12 and 13 are sections taken on the lines 11—11, 12—12, and 13—13 respectively of

Fig. 6 and showing the manner in which the fold-forming disks and edge guides cooperate to form the double fold that is sewed to give an export seam.

Referring to the drawings and more particularly to Fig. 3, the folded bag material 10 is moved down a sloping feed table 18 with the free edges 12 and 14 extending rearwardly, and the material is so positioned transversely of the feed table that the edges 12 and 14 engage a feed roll 20. As described more fully hereafter, the feed roll 20 causes the bag material to be fed at a controlled rate to the fold former 22 wherein the edges 12 and 14 are folded to form the export fold 16. The seam former 22 is provided with a longitudinal slot 23 through which a part of the feed table 18 extends to support the main portion of the bag material as it passes through the fold former. This extension of feed table 18 into the fold former is shown only in Figs. 5, 7 and 11-13 of the drawings, since in Fig. 3 and other figures, it tends to hide working parts of the fold former that it is desirable to show.

After the double fold 16 has been formed, it is pressed and fed between the lower portion of feed table 18 and a conveyer 24 in such manner that the conveyer moves the bag material downwardly along the lower portion of the feed table to and along a horizontal sewing table 26 to a sewing machine. Since the sewing machine may be of a conventional type, only the presser foot 28 of the machine is shown in the drawings.

The construction of fold former 22 and the mounting of feed roll 20 are best shown in Figs. 5, 6 and 7 of the drawings. Referring to these figures, the feed roll 20 is mounted on a rotatable shaft 30 to which it is keyed by a key 32 in such manner that the feed roll is rotated by the shaft but can be positioned axially of the shaft. Shaft 30 passes through and is supported by a journal bearing 34 that is fixed to an arm 36 swivelly mounted on a rotatable shaft 38 which extends through and is supported by a journal bearing 40 and by a side wall of the casing 40 of fold former 22. Thus the feed roll 20 is movable with respect to the fold former casing 40 and the feed table 18, and may ride up over the bag material as the material passes between feed roll and feed table. The feed roll is caused to bear against the upper surface of the feed table, or of the bag material, by the action of gravity.

In order to ensure proper alignment of the feed roll 20 with the interior parts of the fold former, the surface of the roll is provided with a series of grooves 42 into which the ends of a series of vertical disengaging plates of a disengaging comb 44 extend. The construction and operation of the disengaging comb 44 is described more fully below.

The feed table 18 extends through an opening 46 in the fold former casing 40 to a point adjacent to the mechanism that separates the free edges 12 and 14 of the bag material. This mechanism consists of two series of separator disks comprising an upper set of toothed wheels 48 which are keyed to the shaft 38 by a key 50 and a lower set of toothed wheels 52 that are keyed to a shaft 54 by a key 56. The construction is such that the upper separator disks 48 and lower separator disks 52 may be rotated by the shafts 38 and 54 respectively, but are axially movable with respect to these shafts. The disks 48 and 52 are positioned to engage respectively the upper and lower free edges of the bag material and are arranged with their peripheries tangent to one another,

but with their teeth in staggered relation. That is to say, the points of the teeth of the disks 48 are positioned opposite the spaces between the teeth of the disk 52 and vice versa.

The disengaging comb 44, previously referred to, comprises a series of vertical disengaging plates, the number and positions of the disengaging plates being such that a disengaging plate is located on both sides of each separator disk 48. The disengaging plates of comb 44 are mounted on a shaft 58 which is supported at its ends in the casing 40 of the fold former, and are free to rotate with respect to the shaft 58. Each of the disengaging plates of the comb 44 is provided with a depending arcuate shearing edge 60 which has a radius of curvature slightly greater than that of the separator disks 48. The comb 44 is normally so positioned that the teeth of the separator disks extend somewhat below the bottom portions of the shearing edges 60 of the comb, whereas the upper portions of the shearing edges extend beyond the disk teeth.

The lower set of separator disks 52 is provided with a disengaging comb 62 which is similar to the comb 44 and is mounted on and rotatable about a shaft 64. The disengaging plates of the comb 62 are provided with upwardly extending arcuate shearing edges 65 which have radii of curvature somewhat greater than the radii of curvature of the separator disks 52.

The manner in which the separator disks 48 and 52 and combs 44 and 62 cooperate to separate the edges of the bag material is best shown in Fig. 10 of the drawings. Referring to Fig. 10, as the bag material passes between the separator disks 48 and 52 the peripheral teeth of the separator disks 48 engage transverse fibres of the upper edge portion 12 of the bag material and the peripheral teeth of the lower separator disks 52 engage transverse fibres of the lower edge portion 14 of the bag material. As the disks 48 and 52 are rotated, the edge portions of the material are separated from one another. Upon continued rotation of disks 48 and 52, the peripheral teeth of the separator disks gradually move into the spaces between the plates of the combs 44 and 62 respectively, and the edge portions of the bag material are released by being pushed off the teeth of the separator disks, or, in some cases, the transverse fibres may be sheared by the cooperative action of the separator disks and the disengaging plates of the combs. In order to prevent the edges 12 and 14 from coming together again when they have been released from the separator disks, a guide 66 is provided having a leading edge 68 that extends part way between the two sets of separator disks as clearly shown in Figs. 6 and 10.

Referring again to Fig. 5 and also to Fig. 8, the disengaging plates of the comb 44 and the separator disks 48 are spring-pressed together. The inner end of bearing 70 forms an abutment against which the plates and disks are pressed by a spring 72 which bears against the front plate of the comb 44 and also against an adjusting nut 74 threaded onto a bushing 76 mounted on the casing 40. By adjustment of the nut 74 the tension of spring 72 may be adjusted to regulate the force with which the separator disks 48 and disengaging plates of comb 44 are pressed together. This force is so regulated as to ensure proper shearing action and at the same time permit rotation of the separator disks. Since the disengaging plates of the comb 44 extend into the grooves 42 of the feed roll 20, proper alignment of the feed roll and separator disks

is also ensured. The lower separator disks 52 and disengaging plates of comb 62 are pressed together by an adjustable spring (not shown) similar to the spring 72.

It is apparent that the point of disengagement of the bag material from the separator disks is determined by the relative positions of the separator disks 48 and the comb 44 and also by the relative positions of the separator disk 52 and the comb 62. In order to regulate these points of disengagement, the combs 44 and 62 are made adjustable. Referring to Figs. 6 and 9 of the drawings, each of the disengaging plates of comb 44 is provided with a threaded adjusting screw 78 having a lower end which extends into the top of the disengaging plate and is provided with a groove 80 into which the disengaging plate is peened to provide a connection between the screw and plate which permits rotation of the screw but prevents axial movement of the screw relative to the plate. Each of the screws 78 passes through a nut 82 fixed in the casing 40 of the seam former and extends upwardly to the exterior of the casing. At its top each screw 78 is provided with a kerf 84 by means of which the screw may be rotated to position the disengaging plate of the comb 44. As shown in Fig. 8 the disengaging plates of comb 44 are provided with central holes 86 which are somewhat larger in diameter than shaft 38 to permit the desired adjustment of the comb 44 relative to the shaft 38 and separator disks 48. The lower comb 62 is provided with similar adjusting screws 88 that are similarly mounted in the fixed nuts 90 and may be rotated to position the disengaging plates of the comb 62 relative to the separator disks 52.

The driving mechanism for driving the feed roll 20 and separator disks 48 and 52 is shown in Figs. 4 and 5 of the drawings. Referring to these figures, there is provided in the lower central portion of the fold former 22 a drive shaft 92 rotatably mounted in the casing 40 and driven by a suitable motor (not shown). Fixed to the drive shaft 92 there is a bevel gear 94 which engages a pair of bevel gears 96 and 98 fixed to the diagonal shafts 100 and 102 respectively. The shaft 100 is rotatably mounted on the casing 40 by means of the journal bearings 104 and 106, and the shaft 102 is mounted in the journal bearings 108 and 110 which are fixed to the casing 40. At its upper end shaft 102 is provided with a bevel gear 112 that engages a bevel gear 114 on the shaft 54 which also carries a gear 116 that meshes with a similar gear 118 on the shaft 38. To drive the feed roll 20, shaft 38 is provided with a sprocket 120, and shaft 30 is provided with a similar sprocket 122, the sprockets 120 and 122 being interconnected by a chain 124 in such manner that the feed roll 20 is driven from shaft 38. Thus the feed roll 20 and shafts 38 and 54 which carry the separator disks 48 and 52 respectively are positively interconnected to ensure proper synchronization thereof.

After the free edges of the bag material have been separated, they are folded to form a double fold as shown in Figure 2 which is then sewed to produce the export seam. Referring particularly to Figs. 6, 7 and 11 of the drawings, the main portion of the bag material passes between the guide plates 67 and 69 and the free edges of the bag material pass over the guide 66 to the fold-forming disks which comprise an upper male fold-forming disk 126, a lower male fold-forming disk 128, and a female fold-forming member 130 comprising an upper disk 131 and lower disk 133.

that may be interconnected with one another as shown in Fig. 7. The disk 126 is mounted on a shaft 132 that extends upwardly through a movable bearing 134 and is provided at its upper end with a driving gear 136. The disk 128 is fixed to a shaft 138 that extends downwardly through a movable bearing 140 and is provided at its lower end with a driving gear 142. The forming member 130 is fixed to a shaft 144 that extends through an upper bearing 146 and a lower bearing 148. At its upper end shaft 144 is provided with a driving gear 150 that meshes with the gear 136 and at its lower end shaft 144 is provided with a driving gear 152 that meshes with the gear 142. All of the disks 126, 128, 131 and 133 are driven from the drive shaft 92 through the bevel gear 154 fixed to the shaft 92 and the bevel gear 156 fixed to the shaft 144.

The forming member 130 is provided with a deep central groove 158 through which the guide 66 passes. The guide 66 is provided with upper and lower projecting portions 160 and 162 which serve to guide the upper edge of the bag material onto the upper surface of disk 131 and lower surface of disk 133 respectively. The main portion of the bag material is supported on feed table 18 and is guided by guide plates 67 and 69 between the disks 126 and 128. As shown in Figs. 7 and 12 guide plate 67 is provided with a hole 123 that fits over a cylindrical projection 125 of the disk 126 to ensure proper positioning of the guide plate with respect to the disk and guide plate 69 is provided with a hole 127 that fits over a projection 129 of disk 128 for the same purpose.

Still referring to Figs. 7 and 12, the disk 131 is provided with a peripheral forming groove 164 which cooperates with a peripheral forming surface or tongue 166 of the disk 126, and the disk 133 is provided with a peripheral groove 168 which cooperates with the peripheral forming surface or tongue 170 of the disk 128. As the upper layer of the bag material passes between the disk 131 and disk 126, the forming surfaces 164 and 166 cause the edge portion 14 to be folded over to form an external fold. Similarly, as the lower layer of the bag material passes between the disk 133 and the disk 128 the lower edge portion 16 of the bag material is folded over to form a second external fold.

The forming disks 126 and 128 are spring pressed against the forming surfaces of member 130 to ensure proper contact of the fold-forming surfaces of the disks with the bag material. Referring to Figs. 6 and 7 the movable bearing 134 is provided at its upper end with the projecting ears 172 that fit into corresponding grooves or tracks 174 formed in the casing 40 in such manner as to permit transverse sliding movement of the bearing. A compression spring 176 bears against the upper portion of the bearing 134 and also against the casing 40 to cause the bearing 134 to be urged toward the bearing 146 and to cause the forming surface 166 of disk 126 to exert a predetermined force on the forming surface 164 of disk 131. The movable bearing 140 is provided with similar ears 178 that fit into grooves 180 to permit transverse sliding movement of the bearing 140 and a spring 182 similar to the spring 176 urges the forming surface of disks 128 against the forming surface 168 of disk 133.

Referring to Figs. 6 and 13, after leaving the fold-forming disks the main portion of the bag material continues to pass between the guide plates 67 and 69 which cause the bag material

to continue in a desired straight line direction and prevent the material from being carried around with the fold-forming disks as they rotate. The folded edges of the material pass through a forming guide 184 having arms 185 and 187 that overlap the edge portions of the guide plates 67 and 69 and guide the edge portions of the bag material to complete the formation of the double fold. The folded edges leave the discharge ends of forming guide 184 and guide plates 67 and 69 and pass between a pair of press rolls 186 and 188. The upper press roll 186 carries the conveyer 24 and causes the bag material to be moved onto the lower portion 18 of the feed table and out of the fold former casing 40 through a slot 190. The feed table 18 is provided with a knife edge 192 that bears against the surface of lower roll 188 to make sure that the bag material is properly fed onto the feed table 18.

The press rolls 186 and 188 and conveyer 24 are driven from the main drive shaft 92. Referring to Figs. 4, 5 and 6, the shaft 100 is provided at its upper end with a bevel gear 194 that meshes with a bevel gear 196 mounted on a shaft 198 to which the press roll 188 is keyed by a key 200. The shaft 198 also carries a gear 202 which meshes with a gear 204 fixed to a shaft 206 to which the press roll 186 is fixed by a key 208. Thus the press rolls 186 and 188 and conveyer 24 are positively connected to the main drive shaft 92 through which they are also connected to the other moving parts of the apparatus.

The operation of the above-described apparatus is largely apparent from its description. The folded bag material 10 is moved downwardly on the feed table 18 until the free edges of the folded material engage the feed roll 20. It is then moved at a controlled rate into the fold former 22 through the opening 46 in the casing 40 of the seam former. As the material passes between the upper and lower sets of separator disks 48 and 52 the peripheral teeth of the separator disks engage transverse fibres of the upper and lower layers of the bag material respectively and separate the free edges of the material. The edges of the bag material adhere to the separator disks until they have passed to a point beyond the leading edge 68 of the guide 66 and are then disengaged by the combs 44 and 62 respectively. The separator disks and disengaging plates of the combs are held in firm contact with one another by adjustable springs so that if the transverse fibres are not pushed off the teeth of the separator disks, they will be sheared by the cooperative action of the disengaging plates and the teeth. The disengaging combs are made adjustable to ensure that the bag material will be disengaged from the separator disks only after it has passed beyond the leading edge 68 of the guide 66.

The main portion of the bag material moves along an extension of feed table 18 between the guide plates 67 and 69 and the fold-forming disks 126 and 128, whereas the separated edge portions of the material are guided by the upper and lower projecting portions 160 and 162 in such manner that they ride over the upper surface of seam-forming disk 131 and the lower surface of the fold-forming disk 133. The forming surface 166 of disk 126 and forming surface 164 of disk 131 cooperate to cause the edge portion 14 of the bag material to be formed into an external fold, and the forming surface 170 of disk 128 and

forming surface 168 of disk 133 cooperate to cause an external fold to be formed in the free edge 16 of the bag material. The folds thus formed are brought into contact with one another again at the discharge end of the guide 184 and pressed firmly together by the press rolls 186 and 188. The export fold thus formed passes onto the lower portion of feed table 18 and is fed by conveyer 24 to the presser foot 28 of a sewing machine which sews the fold.

It has been found that the apparatus described is capable of operating at relatively high speeds to form an export fold accurately and reliably. The separator disks give a positive separation of the edges of the bag material and the disengaging combs ensure proper disengagement of the edges of the material after they have been separated. The separator disks provide a simple and positive method of forming the desired folds in the material to form an export fold.

Since many embodiments might be made of the present invention and since many changes might be made in the embodiment disclosed herein, it is to be understood that the foregoing description is to be interpreted as illustrative only and not in a limiting sense. Numerous modifications within the scope of the invention will be apparent to those skilled in the art.

I claim:

30. In apparatus for forming the free edges of a piece of folded bag material into a double fold adapted to be sewed by a sewing machine to form an export seam, in combination, separating means for separating said free edges of said bag material, first fold-forming means for receiving one of said free edges of said material from said separating means and forming a fold in said free edge, second fold-forming means for receiving the other of said free edges of said material from said separating means and forming a fold in said other free edge, first guide means positioned between said separating means and said fold-forming means to maintain said two free edges of said material separated as said material passes from said separating means to said fold-forming means, disengaging means for disengaging said edges from said separating means when said edges have begun to pass over said first guide means, second guide means for guiding said edge folds from said first and second fold-forming means into contact with one another and pressure-exerting means for pressing said folds together to form said double fold.
35. In apparatus for forming the free edges of a piece of folded bag material into a double fold adapted to be sewed by a sewing machine to form an export seam, in combination, separating means for separating said free edges of said bag material, first fold-forming means for receiving one of said free edges of said material from said separating means and forming a fold in said free edge, second fold-forming means for receiving the other of said free edges of said material from said separating means and forming a fold in said other free edge, first guide means positioned between said separating means and said fold-forming means to maintain said two free edges of said material separated as said material passes from said separating means to said fold-forming means, disengaging means for disengaging said edges from said separating means when said edges have begun to pass over said first guide means, second guide means for guiding said edge folds from said first and second fold-forming means into contact with one another and pressure-exerting means for pressing said folds together to form said double fold.
40. In apparatus for forming the free edges of a piece of folded bag material into a double fold adapted to be sewed by a sewing machine to form an export seam, in combination, separating means for separating said free edges of said bag material, first fold-forming means for receiving one of said free edges of said material from said separating means and forming a fold in said free edge, second fold-forming means for receiving the other of said free edges of said material from said separating means and forming a fold in said other free edge, first guide means positioned between said separating means and said fold-forming means to maintain said two free edges of said material separated as said material passes from said separating means to said fold-forming means, disengaging means for disengaging said edges from said separating means when said edges have begun to pass over said first guide means, second guide means for guiding said edge folds from said first and second fold-forming means into contact with one another and pressure-exerting means for pressing said folds together to form said double fold.
45. In apparatus for forming the free edges of a piece of folded bag material into a double fold adapted to be sewed by a sewing machine to form an export seam, in combination, separating means for separating said free edges of said bag material, first fold-forming means for receiving one of said free edges of said material from said separating means and forming a fold in said free edge, second fold-forming means for receiving the other of said free edges of said material from said separating means and forming a fold in said other free edge, first guide means positioned between said separating means and said fold-forming means to maintain said two free edges of said material separated as said material passes from said separating means to said fold-forming means, disengaging means for disengaging said edges from said separating means when said edges have begun to pass over said first guide means, second guide means for guiding said edge folds from said first and second fold-forming means into contact with one another and pressure-exerting means for pressing said folds together to form said double fold.
50. In apparatus for forming the free edges of a piece of folded bag material into a double fold adapted to be sewed by a sewing machine to form an export seam, in combination, separating means for separating said free edges of said bag material, first fold-forming means for receiving one of said free edges of said material from said separating means and forming a fold in said free edge, second fold-forming means for receiving the other of said free edges of said material from said separating means and forming a fold in said other free edge, first guide means positioned between said separating means and said fold-forming means to maintain said two free edges of said material separated as said material passes from said separating means to said fold-forming means, disengaging means for disengaging said edges from said separating means when said edges have begun to pass over said first guide means, second guide means for guiding said edge folds from said first and second fold-forming means into contact with one another and pressure-exerting means for pressing said folds together to form said double fold.
55. In apparatus for forming the free edges of a piece of folded bag material into a double fold adapted to be sewed by a sewing machine to form an export seam, in combination, separating means for separating said free edges of said bag material, first fold-forming means for receiving one of said free edges of said material from said separating means and forming a fold in said free edge, second fold-forming means for receiving the other of said free edges of said material from said separating means and forming a fold in said other free edge, first guide means positioned between said separating means and said fold-forming means to maintain said two free edges of said material separated as said material passes from said separating means to said fold-forming means, disengaging means for disengaging said edges from said separating means when said edges have begun to pass over said first guide means, second guide means for guiding said edge folds from said first and second fold-forming means into contact with one another and pressure-exerting means for pressing said folds together to form said double fold.
60. In apparatus for forming the free edges of a piece of folded bag material into a double fold adapted to be sewed by a sewing machine to form an export seam, in combination, separating means for separating said free edges of said bag material, first fold-forming means for receiving one of said free edges of said material from said separating means and forming a fold in said free edge, second fold-forming means for receiving the other of said free edges of said material from said separating means and forming a fold in said other free edge, first guide means positioned between said separating means and said fold-forming means to maintain said two free edges of said material separated as said material passes from said separating means to said fold-forming means, disengaging means for disengaging said edges from said separating means when said edges have begun to pass over said first guide means, second guide means for guiding said edge folds from said first and second fold-forming means into contact with one another and pressure-exerting means for pressing said folds together to form said double fold.
65. In apparatus for forming the free edges of a piece of folded bag material into a double fold adapted to be sewed by a sewing machine to form an export seam, in combination, separating means for separating said free edges of said bag material, first fold-forming means for receiving one of said free edges of said material from said separating means and forming a fold in said free edge, second fold-forming means for receiving the other of said free edges of said material from said separating means and forming a fold in said other free edge, first guide means positioned between said separating means and said fold-forming means to maintain said two free edges of said material separated as said material passes from said separating means to said fold-forming means, disengaging means for disengaging said edges from said separating means when said edges have begun to pass over said first guide means, second guide means for guiding said edge folds from said first and second fold-forming means into contact with one another and pressure-exerting means for pressing said folds together to form said double fold.
70. In apparatus for forming the free edges of a piece of folded bag material into a double fold adapted to be sewed by a sewing machine to form an export seam, in combination, separating means for separating said free edges of said bag material, first fold-forming means for receiving one of said free edges of said material from said separating means and forming a fold in said free edge, second fold-forming means for receiving the other of said free edges of said material from said separating means and forming a fold in said other free edge, first guide means positioned between said separating means and said fold-forming means to maintain said two free edges of said material separated as said material passes from said separating means to said fold-forming means, disengaging means for disengaging said edges from said separating means when said edges have begun to pass over said first guide means, second guide means for guiding said edge folds from said first and second fold-forming means into contact with one another and pressure-exerting means for pressing said folds together to form said double fold.
75. In apparatus for forming the free edges of a piece of folded bag material into a double fold adapted to be sewed by a sewing machine to form an export seam, in combination, separating means for separating said free edges of said bag material, first fold-forming means for receiving one of said free edges of said material from said separating means and forming a fold in said free edge, second fold-forming means for receiving the other of said free edges of said material from said separating means and forming a fold in said other free edge, first guide means positioned between said separating means and said fold-forming means to maintain said two free edges of said material separated as said material passes from said separating means to said fold-forming means, disengaging means for disengaging said edges from said separating means when said edges have begun to pass over said first guide means, second guide means for guiding said edge folds from said first and second fold-forming means into contact with one another and pressure-exerting means for pressing said folds together to form said double fold.

said separating means after said material has passed the leading edge of said first guide means, second guide means for guiding said edge folds from said first and second fold-forming means into contact with one another and pressure-exerting means for pressing said folds together to form said double seam.

3. In apparatus for forming the free edges of a piece of folded bag material into an export double fold adapted to be sewed by a sewing machine to form an export seam, in combination, first rotatable toothed wheel means positioned to engage one free edge of said bag material, second rotatable toothed wheel means positioned to engage the other edge of said bag material, means for rotating said first and second toothed wheel means to cause said toothed wheel means to separate said edges from one another, first fold-forming means for receiving one of said free edges of said material from said first toothed wheel means and forming an external fold in said edge, second fold-forming means for receiving the other of said free edges from said second toothed wheel means and forming an external fold in said other free edge, guide means for guiding said edge folds from said first and second forming means into contact with one another and pressure-exerting means for receiving said edge folds from said guide means and pressing said folds together to form said double fold.

4. In apparatus for forming the free edges of a piece of folded bag material into a double fold adapted to be sewed by a sewing machine to form an export seam, in combination, first toothed wheel means positioned to engage one free edge of said bag material, second toothed wheel means positioned to engage the other free edge of said material, means for rotating said first and second toothed wheel means to cause said toothed wheel means to separate one of said edges from the other edge, first fold-forming means for receiving one of said free edges from said first toothed wheel means and forming an external fold in said edge, second fold-forming means for receiving the other edge of said bag material from said second toothed wheel means and forming an external fold in said other edge, first guide means positioned between said toothed wheel means and said fold-forming means to maintain said edges separated from one another as they pass from said toothed wheel means to said fold-forming means, disengaging means for disengaging said edges from said toothed wheel means after said edges have begun to pass over said first guide means, second guide means for guiding the folds formed by said first and second fold-forming means into contact with one another and pressure-exerting means for receiving said folds from said second guide means and pressing said folds together to form said double fold.

5. In apparatus for forming the free edges of a piece of folded bag material into a double fold adapted to be sewed by a sewing machine to form an export seam, in combination, first toothed wheel means positioned to engage one free edge of said bag material, second toothed wheel means positioned to engage the other free edge of said material, means for rotating said first and second toothed wheel means to cause said toothed wheel means to separate one of said edges from the other edge, first fold-forming means for receiving one of said free edges from said first toothed wheel means and forming an external fold in said edge, second fold-forming means for receiving the other edge of said bag material from said

second toothed wheel means and forming an external fold in said other edge, first guide means positioned between said toothed wheel means and said fold-forming means to maintain said edges separated from one another as they pass from said separating means to said fold-forming means, disengaging means for disengaging said edges from said toothed wheel means after said edges have begun to pass over said first guide means, adjusting means for adjusting the position of said disengaging means with respect to said toothed wheel means and said first guide means to ensure disengagement of said material from said toothed wheel means after said material has begun to pass over said first guide means, second guide means for guiding the folds formed by said first and second fold-forming means into contact with one another and pressure-exerting means for receiving said folds from said second guide means and pressing said folds together to form said double fold.

6. In apparatus for forming the free edges of a piece of folded bag material into a double fold adapted to be sewed by a sewing machine to form an export seam, in combination, a first series of co-axial toothed wheels positioned to engage one side of said folded bag material at one of the free edges thereof, a second series of co-axial toothed wheels positioned to engage the other side of said folded bag material near the other free edge thereof, means for rotating said toothed wheels to cause said toothed wheels to separate said free edges of said bag material, first fold-forming means for receiving one of said free edges of said material from said first series of toothed wheels and forming an external fold in said free edge, second fold-forming means for receiving the other of said free edges from said second series of co-axial toothed wheels and forming an external fold in said other edge of said material, guide means for guiding the edge folds formed by said first and second fold-forming means into contact with one another and pressure-exerting means for receiving said folds from said guide means and pressing said folds together to form said double fold.

7. In apparatus for forming the free edges of a piece of folded bag material into a double fold adapted to be sewed by a sewing machine to form a double fold, in combination, a first series of co-axial toothed wheels positioned to engage one side of said folded bag material at one of the free edges thereof, a second series of co-axial toothed wheels positioned to engage the other side of said folded bag material near the other free edge thereof, means for rotating said toothed wheels to cause said toothed wheels to separate, said free edges of said bag material, first fold-forming means for receiving one of said free edges of said material from said first series of toothed wheels and forming an external fold in said free edge, second fold-forming means for receiving the other of said free edges from said second series of co-axial toothed wheels and forming an external fold in said other edge of said material, a first series of disengaging members positioned between the toothed wheels of said first series of toothed wheels and adapted to cooperate therewith to disengage said material from said toothed wheels after said free edges have been separated, a second series of disengaging members positioned between the toothed wheels of said second series of wheels and adapted to cooperate with said second series of wheels to separate the other of said free edges from said second series of wheels after said

11

free edges have been separated, guide means for guiding the folds formed by said first and second fold-forming means into contact with one another, and pressure-exerting means for receiving said folds from said guide means and pressing said folds together to form said double fold.

8. In apparatus for forming the free edges of a piece of folded bag material into a double fold adapted to be sewed by a sewing machine to form a double fold, in combination, a first series of co-axial toothed wheels positioned to engage one side of said folded bag material at one of the free edges thereof, a second series of co-axial toothed wheels positioned to engage the other side of said folded bag material near the other free edge thereof, means for rotating said toothed wheels to cause said toothed wheels to separate said free edges of said bag material, first fold-forming means for receiving one of said free edges of said material from said first series of toothed wheels and forming an external fold in said free edge, second fold-forming means for receiving the other of said free edges from said second series of co-axial toothed wheels and forming an external fold in said other edge of said material, a separating member mounted between said toothed wheels and said fold-forming means for maintaining said free edges separated from one another as they pass from said toothed wheels to said fold-forming means, said separating member having a leading edge extending to a point between said first and second series of toothed wheels, a first series of disengaging members positioned between the toothed wheels of said first series of wheels for disengaging said one free edge of said bag material from said first series of wheels, a second series of disengaging members positioned between the toothed wheels of said second series of toothed wheels and adapted to cooperate with the toothed wheels of said second series to disengage said other edge of said material from said second series of wheels, first adjusting means for adjusting the position of said first series of disengaging members with respect to said first series of toothed wheels to ensure disengagement of said material from said first series of toothed wheels after said material has passed said leading edge of said separating member, second adjusting means for adjusting the position of said second series of disengaging members with respect to said second series of toothed wheels to ensure disengagement of said material from said second series of toothed wheels after said material has passed said leading edge of said separating member, guide means for guiding the edge folds formed by said first and second fold-forming means into contact with one another and pressure-exerting means for receiving said folds from said guide means and pressing said folds together to form said double fold.

9. In apparatus for forming the free edges of a piece of folded bag material into a double fold adapted to be sewed by a sewing machine to form an export seam, in combination, separating means for separating said free edges of said bag material, a first pair of rotatable fold-forming disks adapted to receive one of said separated free edges of said bag material therebetween, a second pair of rotatable fold-forming disks adapted to receive the other separated free edge of said bag material therebetween, means for rotating said two pairs of disks to cause said disks to form external folds in said free edges of said material, guide means for guiding

12

the folds formed by said seam-forming disks into contact with one another and pressure-exerting means for receiving said folds from said guide means and pressing said folds together to form said double fold.

5 10. In apparatus for forming the free edges of a piece of folded bag material into a double fold adapted to be sewed by a sewing machine to form an export seam, in combination, separating means for separating said free edges of said bag material, a first pair of rotatable fold-forming disks adapted to receive therebetween one separated edge of said bag material from said separating means, a second pair of rotatable fold-forming disks adapted to receive therebetween the other separated free edge of said material from said separating means, one disk of each of said pairs of disks having a peripheral groove and the other disk of each of said pairs of disks having a peripheral tongue cooperating with the groove in said other disk to cause bag material passing between said disks to be folded in an external fold, means for rotating said first and second pairs of disks to form said external folds in said free edges of said material, guide means for guiding the edge folds formed by said seam-forming disks into contact with one another and pressure-exerting means for receiving said folds from said guide means and pressing said folds together to form a double fold.

20 11. In apparatus for forming the free edges of a piece of folded bag material into a double fold adapted to be sewed by a sewing machine to form an export seam, in combination, separating means for separating said free edges of said bag material, a first pair of rotatable fold-forming disks adapted to receive therebetween one separated edge of said bag material from said separating means, a second pair of rotatable fold-forming disks adapted to receive therebetween the other separated free edge of said material from said separating means, one disk of each of said pairs of disks having a peripheral groove and the other disk of each of said pairs of disks having a peripheral tongue cooperating with the groove in said other disk to cause bag material passing between said disks to be folded in an external fold, means for rotating said first and second pairs of disks to form said external folds in said free edges of said material, resilient force-exerting means positioned to exert a resilient force on one disk of each of said pairs of disks to hold the disks of each pair of disks in resilient contact with one another, guide means for guiding the edge folds formed by said fold-forming disks into contact with one another and pressure-exerting means for receiving said folds from said guide means and pressing said folds together to form said double fold.

25 12. In apparatus for forming the free edges of a piece of folded bag material into a double fold adapted to be sewed by a sewing machine to form an export seam, mechanism for separating said free edges from one another comprising, in combination, first rotatable toothed wheel means positioned to engage one side of said bag material near one of said free edges, second rotatable toothed means positioned to engage the other side of said folded bag material near the other free edge thereof and means for rotating said first and second toothed wheel means to cause said toothed wheel means to separate said free edges of said folded bag material.

30 13. In apparatus for forming the free edges of a piece of folded bag material into a double fold

13

adapted to be sewed by a sewing machine to form an export seam, mechanism for separating said free edges from one another comprising, in combination, first rotatable toothed wheel means positioned to engage one side of said folded bag material near one of said free edges, second rotatable toothed wheel means positioned to engage the other side of said folded bag material near the other free edge thereof, means for rotating said toothed wheel means to cause said toothed wheel means to separate said free edges of said bag material and disengaging means cooperating with said toothed wheel means to disengage said bag material from said toothed wheel means after said free edges have been separated.

14. In apparatus for forming the free edges of a piece of folded bag material into a double fold adapted to be sewed by a sewing machine to form an export seam, mechanism for separating said free edges from one another comprising, in combination, a first series of co-axial toothed wheels positioned to engage one side of said folded bag material near one of said free edges, a second series of co-axial toothed wheels positioned to engage the other side of said folded bag material near the other of said free edges, a first series of disengaging members positioned between the toothed wheels of said first series of wheels and adapted to cooperate with said toothed wheel to disengage said one free edge of said material from said toothed wheels after it has been separated from said other free edge, a second series of disengaging members positioned between the toothed wheels of said second series of toothed wheels and adapted to cooperate with the toothed wheels of said second series to disengage said other free edge of said material from the toothed wheels of said second series when said other edge has been separated from said one edge and means for rotating said toothed wheels to cause said toothed wheels to separate said free edges of said material.

15. In apparatus for forming the free edges of a piece of folded bag material into a double fold adapted to be sewed by a sewing machine to form an export seam, mechanism for separating said free edges from one another comprising, in combination, a first series of co-axial toothed wheels positioned to engage one side of said folded bag material near one of said free edges, a second series of coaxial toothed wheels positioned to engage the other side of said folded bag material near the other of said free edges, a first series of disengaging members positioned between the toothed wheels of said first series of wheels and adapted to cooperate with said toothed wheel to disengage said one free edge of said material from said toothed wheels after it has been separated from said other free edge, a second series of disengaging members positioned between the toothed wheels of said second series of toothed wheels and adapted to cooperate with the toothed wheels of said second series to disengage said other free edge of said material from the toothed wheels of said second series when said other edge has been separated from said one edge, first adjusting means for adjusting said first series of

14

disengaging members to vary the point at which said material is disengaged from said first series of toothed wheels, second adjusting means for adjusting the position of said second series of disengaging members to vary the point at which said material is disengaged from said second series of toothed wheels, and means for rotating said first and second series of toothed wheels to cause said toothed wheels to separate the free edges of said folded material.

16. In apparatus for forming the free edges of a piece of folded bag material into a double fold adapted to be sewed by a sewing machine to form an export seam, mechanism for forming a fold

15 in each of said free edges of said material comprising, in combination, a first pair of rotatable disks mounted with their peripheries in contact with one another and adapted to receive one free edge of said bag material therebetween, a 20 second pair of rotatable disks mounted with their peripheries in contact with one another adapted to receive the other free edge of said bag material therebetween, one disk of each of said pairs of disks having a peripheral groove and the other 25 disk of said pairs of disks having a peripheral tongue cooperating with the groove in the other disk of said pair to cause bag material passing between said disks to be folded into an external fold, and means for rotating said first and second 30 pairs of disks to form said external folds in said free edges of said material.

17. In apparatus for forming the free edges of a piece of folded bag material into a double fold adapted to be sewed by a sewing machine

35 to form an export seam, mechanism for forming a fold in each of said free edges of said free material comprising, in combination, a first pair of rotatable disks mounted with their peripheries in contact with one another and adapted to re-

40 ceive one free edge of said bag material therebetween, a second pair of rotatable disks mounted with their peripheries in contact with one another adapted to receive the other free edge of said bag material therebetween, one disk of each

45 of said pairs of disks having a peripheral groove and the other disk of said pairs of disks having a peripheral tongue cooperating with the groove in the other disk of said pair to cause bag material passing between said disks to be folded into

50 an external fold, spring means for urging one disk of each of said pairs of disks into contact with the other disk of said pair, to provide a resilient contact between said disks and means for urging the disks of said first and second pairs

55 of disks to form said external folds in said free edges of said material.
